United States Patent Office.

THOMAS LING, OF HARTFORD, CONNECTICUT.

Letters Patent No. 96,329, dated November 2, 1869; antedated October 27, 1869.

IMPROVEMENT IN PUMP-VALVES.

The Schedule referred to in these Letters Patent and making part of the same.

To all whom it may concern:

Be it known that I, THOMAS LING, of Hartford, in the county of Hartford, and the State of Connecticut, have invented a new and useful Improvement in Self-Adjusting or Anchoring-Pumps; and I declare the following to be a full and exact description thereof, reference being had to the accompanying drawings and to the letters of reference marked thereon, forming a part of this specification.

The main features of the pump upon which I have made an improvement are those of the pump patented by me, March 27, 1855; and

The improvement aimed at herein has two parts—the one an improved valve for said pump, and the other the substitution of an axle and rotating handle in the place of the old pump-arm or lever.

The same letters always indicate the same parts in all the drawings.

Figure 1 is a sectional view of the whole pump.

Figure 2 is a plan view of the top of the valve, which is claimed as an improvement.

Figure 3 is a view of the bottom of the valve.

In the drawings—

a is a stanchion, or support for the axle *b*, to which are fastened, on the one end, the crank *c*, and on the other side the disk *d*, which is attached, by means of the connecting-rod *e*, to the pipe and pump at *f*. One of the features of the improvement herein claimed is the substitution of this crank, axle, disk, and connecting-rod for raising and lowering the pump, in the place of the old-fashioned arm, or lever. The other feature of improvement claimed is the peculiarly-constructed valve, represented by the colored sections in fig. 1, and by figs. 2 and 3.

A is the piston-rod, (of metal, of course,) with flange all around it, extending to the inner circumference of

the pump, with holes at *x* for the water to gush through when the valve or piston is descending.

B, in red lines, is the core, fitting upon *A*, and fastened to it by the cap *s*, with the screw *i* in its centre.

C, in blue lines, is an outside rim, made in sections. In this case, there are four of these sections, the partitions of which are the heavy blue lines *a'*, in fig. 2.

The core *B* has four lugs on its circumference, *o o o o*, which fit loosely into as many notches, or jogs of the rim *C*. These notches, or jogs are deeper than the depth of the lugs *o*, allowing this rim to rise when the valve or piston is descending, and so let the water through into the upper part of the pump, through the open places *m*.

n is a wire, made of brass or steel, which serves as a spring to keep the piston expanded. It is kept in place by being run through holes in thin webs *y*.

The yellow sectioning in fig. 1, represents a leather ring, running quite around the inner circumference of the pump, fastened to the bottom of all four sections of the rim *C* by rivets, and it serves both as a stopper over the holes *x* and to keep the piston tight in the pump.

I claim, as my invention—

The pump-valve, composed of the rod *A*, with the flange perforated at *x*; the core *B*, with the openings *m* and the lugs *o*; the rim *C*, in sections, with the notches for lugs *o* and the thin webs *y*; the cap *s* and screw *i*; the leather ring *r*, and the wire spring *n*, all arranged and constructed as described, for the purpose described.

Dated the 31st day of December, 1868.

THOMAS LING.
